UNITED STATES PATENT OFFICE

143,103

DESIGN FOR A SPRING-CLIP HANGER

George Yates, Glendale, Calif.

Application April 30, 1945, Serial No. 119,310

Term of patent 14 years

(Cl. D80—8)

To all whom it concern:

Be it known that I, George Yates, a citizen of the United States and a resident of Glendale, California, have invented a new, original, and ornamental Design for a Spring-Clip Hanger, of which the following is a specification, reference being had to the accompanying drawing, forming part thereof.

Referring to the drawing:

Figure 1 is an elevation of a spring-clip hanger,

showing my new design, as viewed from the left of Figure 2;

Figure 2 is a side elevational view of the device; and

Figure 3 is an elevation as viewed from the right of Figure 2.

I claim:

The ornamental design for a spring-clip hanger, as shown.

GEORGE YATES.
